United States Patent Office

Des. 203,230
Patented Dec. 14, 1965

203,230

BOX OR SIMILAR ARTICLE

George A. Rutledge, Richmond, Va., assignor to Reynolds Metals Company, Richmond, Va., a corporation of Delaware

Filed July 15, 1964, Ser. No. 80,880

Term of patent 14 years

(Cl. D58—12.6)

FIG.1

FIGURE 1 is a perspective view of a box or similar article, embodying my new design;

The bottom is plain and unornamented and the side and end not shown in FIG. 1 are the same in appearance as the side and end shown.

I claim:

The ornamental design for a box or similar article, as shown and described.
